UNITED STATES PATENT OFFICE

2,207,066

PERIODIC SWITCH

Walter Millsap, Los Angeles, Calif.

Application October 12, 1936, Serial No. 105,185

1 Claim. (Cl. 200—24)

This invention relates to periodic switches.

The general object of the invention is to provide an electrically operated periodic switch which is particularly adapted to operate a time keeping mechanism.

Other objects and advantages of my invention will be apparent from the following description taken in connection with the accompanying drawing, wherein:

10 Fig. 1 is a front view of a labor time register embodying the features of my invention;

Fig. 2 is a fragmentary side elevation showing the actuating member;

15 Fig. 3 is a fragmentary top plan view showing the actuating member;

Fig. 4 is a section taken on line 4—4 Fig. 2, and

Fig. 5 is a section taken on line 5—5 Fig. 2.

Referring to the drawing by reference character I have indicated one embodiment of my improved time device generally at 10. As shown the device 10 is mounted in a cabinet 12 having a front panel 13 on which I arrange a plurality of man hour labor totalizers 14, a plurality of 25 job hour indicators 15, a man hour totalizer 16, and a plurality of job selector devices 17. Also mounted on the front panel I provide an employee's lock device 18 for controlling each of the man hour indicators and a master lock device 19 30 for controlling the entire unit. Furthermore the device 10 includes a suitable clock mechanism of any desired type as indicated at 20.

Mounted on the wall portion 21 of the clock 20 I provide a pair of spaced lugs 22 which have an arm member 23 pivotally secured thereto as at 24. The free end of the arm member 23 has an aperture 25 therein (see Fig. 4). One fast rotating shaft 26 of the clock mechanism 20 extends through the wall 21 and is secured to a 40 member 27 as by a pin 28. This member 27 is made of suitable electrical insulating material. Rotatably mounted in the upper portion of the member 27 I provide a shaft 30 which passes through the aperture 25 of the arm member 23. A suitable electrical insulating means 31 is provided between the ends of the shafts 26 and 30.

Surrounding the shaft 30 and spaced from the wall 21 I provide a contact plate 32 which is 50 made of a suitable electrical insulating material and is supported by legs 33. Mounted on the shaft 30 adjacent the member 27 I provide a disk 34 which is secured to the shaft as by a pin 35 and between the plate 32 and the disk 34 I provide a suitable electrical insulating sleeve 36

around the shaft 30. The plate 32 has a plurality of electrical contact members 37 thereon which are shown as four in number although the number may be varied to suit the requirements.

Suitably secured to the shaft 30 I provide a wiper arm or controller 38 which is adapted to visit and engage the contacts 37. Spaced from the contact plate 32 I provide a boss 39 which is supported by legs 40 shown as integral with the contact plate 32. Positioned in a suitable recess 10 in the boss 39 I provide a metal sleeve 41 which has a recess 42 therein in which a carbon member 43 is positioned.

Positioned between the inner end of the carbon member 43 and the bottom of the recess 42 I 15 provide a coil spring 44 for resiliently urging the carbon member 43 into engagement with the end of the shaft 30. The sleeve 41 is provided with a contact screw 45 for securing thereto an electrical wire.

The member 27 has an arm 46 projecting therefrom and terminating beyond the periphery of the disk 34 where it has a dog member 47 pivotally secured thereto as at 48. A flat spring member 49 has one end secured to the arm 46 25 and the opposite end engages the dog 47 and resiliently urges it into engagement with the periphery of the disk 34 (see Fig. 4).

In its periphery the disk 34 is notched as at 50. Adjacent the shaft 30 the arm 23 has a depending outwardly directed lip 51 thereon (see Fig. 5) the outer end 52 of which extends to the periphery of the disk 34. Intermediate the pivot 24 and the aperture 25 the arm member 23 has an aperture 53 therein through which a 35 shaft 54 of the clock mechanism 20 projects. This shaft 54 is so geared to the clock mechanism it makes one complete revolution periodically for instance say every six minutes or in other words every tenth of an hour. Secured 40 to the shaft above the arm member 23 I provide a cam disk 55 the under face of which has a notch 56 therein. Mounted on the arm 23 I provide an upstanding finger portion 57 which is below the cam disk 55. Intermediate the shaft 30 45 and the shaft 54 and between the arm member 23 and the wall 21 I provide a coil spring member 58 which resiliently urges the arm member 23 upwardly and the finger portion 57 into engagement with the cam disk 55.

When the clock 20 is operated and the finger portion 57 engages the under side of the cam disk 55 it retains the arm 23 in an inward position which in turn retains the lip 51 in a position adjacent the disk 34. When the notch 56 55

of the cam disk 55 is opposite to the finger portion 57 the latter is moved upwardly by the spring 58 into the notch 56, whereupon the lip 51 is raised above the dog member 47 whereupon when the dog matches the notch 50 in the disk 34 it enters the notch 50 and rotates the disk 34 thereby rotating the shaft 30.

The notch 56 is so disposed that the arm 23 is moved to a lowered position again before the shaft 30 has made one complete revolution whereupon as the dog 47 approaches the end of one complete revolution the lip 51 moves it out engagement with the notch 50 in the disk 34.

As the shaft 30 is rotated the wiper arm 38 thereon makes one complete swing around the contact plate 32 engaging each of the contact members 37 in order. From the foregoing it will be apparent that the wiper arm engages the contacts 47 once every six minutes, that is every 20 tenth of an hour.

Having thus described my invention I claim:

In an actuating device for a labor time registering system, a clock movement including a fast moving shaft and a slow moving shaft, a fixed contact disk having a plurality of spaced contacts thereon, a shaft axially aligned with said fast moving shaft and supported by said disk, a single wiper arm adapted to engage said contacts in order, said wiper arm having exposed contact means, said exposed contact together with the wiper arm and disk contacts being arranged to form a portion of an electrical circuit, a second disk, means to secure said second disk on said wiper arm shaft, said second disk having a notch in its periphery, said fast moving shaft having a laterally projecting arm thereon, a dog pivotally supported on said arm, resilient means normally urging said dog into engagement with said notched periphery, means to insulate said wiper arm shaft from said fast moving shaft, a clutch arm having one end pivotally supported and remote from said shafts and having its other end disposed adjacent to said second disk, said other end including a portion adapted to restrain said dog from engagement with said notch, means normally urging said clutch arm away from said second disk, a cam on said clutch arm, a cam disk on said slow moving shaft and adapted to engage said cam and maintain said clutch arm adjacent said second disk, said cam disk being notched in one portion to receive said cam whereby said clutch arm is allowed to momentarily move away from said second disk during each revolution of said slow moving shaft.

WALTER MILLSAP.
